ATTORNEY

UNITED STATES PATENT OFFICE.

DAVE FRANKEL, OF CLEVELAND, OHIO.

DESIGN FOR THE SHELL OF A LIGHTING-FIXTURE.

57,221.

Specification for Design.

Patented Mar. 8, 1921.

Application filed May 14, 1919. Serial No. 297,169. Term of patent 14 years.

To all whom it may concern:

Be it known that I, DAVE FRANKEL, a citizen of the United States, residing at 5016 Woodland avenue, Cleveland, in the county of Cuyahoga and State of Ohio, have invented a new, original, and ornamental Design for the Shell of a Lighting-Fixture, of which the following is a specification, reference being had to the accompanying drawings, forming a part thereof.

Figure 1 is a side elevation of a shell for a lighting fixture showing my new design; Fig. 2 is a plan view thereof.

I claim:

The ornamental design for the shell of a lighting fixture, as shown.

DAVE FRANKEL.
